[57] CLAIM

The ornamental design for simulative toy top, as shown and described.

DESCRIPTION

FIG. 1 is a front perspective view of a simulative toy
top showing my new design;

FIG. 2 is a side elevational view of FIG. 1;

FIG. 3 is a side elevational view thereof rotated ninety degrees;

FIG. 4 is a bottom plan view of FIG. 2; and,
FIG. 5 is a fragmentary view of the side opposite that
